Fig. 1.

Fig. 2.

Fig. 3

Fig. 4

Fig. 6

FIGURE 1 is a front perspective view of an ice cream carton showing our new design; and

FIGURE 2 is a front elevational view thereof.

FIGURE 3 is a front perspective view of an ice cream carton showing a modification of our new design; and

FIGURE 4 is a front elevational view thereof.

FIGURE 5 is a front perspective view of an ice cream carton showing another modification of our new design; and

FIGURE 6 is a front elevational view thereof.

The side opposite that shown in FIGURES 1, 3 and 5 is substantially a mirror image of the side shown, while the rear and bottom walls are substantially plain.

The essential feature of the design resides in the particular configuration of the front cover panel which is scored as shown.

This is a continuation of design applications Ser. Nos. 6,152, 6,153, and 6,156, all filed Mar. 10, 1967, and all now abandoned.

We claim:

The ornamental design for an ice cream carton, as shown and described.
